(57) **CLAIM**

The ornamental design for a cover for house shutters, as shown and described.

DESCRIPTION

FIG. 1 is a perspective view of a cover for house shutters showing my new design;

FIG. 2 is a front elevational view thereof;

FIG. 3 is a right side elevational view with the left side being a mirror image thereof;

FIG. 4 is a top view thereof; and,

FIG. 5 is a bottom view thereof.

The rear view is plain and unornamented.
